Primary Examiner—Ian Simmons*Assistant Examiner*—Anna J Burmeister(74) Attorney, Agent, or Firm—Robert C. Montgomery(57) CLAIM

The ornamental design for a decorative attachment for apparel, as shown and described.

DESCRIPTION

FIG. 1 is a perspective view of a decorative attachment for apparel, showing my new design;

FIG. 2 is a top plan view thereof;

FIG. 3 is a side elevational view thereof; and,

FIG. 4 is a front elevational view thereof.

The dashed lines featured in FIGS. 1 and 4 represent a perforated line.

The broken lines shown in the drawings are for illustrative purposes only and form no part of the claimed design.
